CLAIM

We claim the ornamental design for a partition insert, as shown and described.

DESCRIPTION

FIG. 1 is a perspective view of a partition insert, embodying our design;

FIG. 2 is a front view of FIG. 1;

FIG. 3 is a side view of FIG. 1, the opposite side being a mirror image thereof;

FIG. 4 is a cross-section taken along lines 4—4 in FIG. 2, the cross-section showing the contour of the surfaces shown in FIG. 2.

FIG. 5 is a top view of FIG. 1, the bottom view being a mirror image thereof; and

FIG. 6 is a cross-section taken along lines 6—6 in FIG. 2, the cross-section showing a contour of the surfaces in FIG. 2.

FIG. 7 is a perspective view of another partition insert, embodying our design;

FIG. 8 is a front view of FIG. 7;

FIG. 9 is a side view of FIG. 7, the opposite side being a mirror image thereof; and

FIG. 10 is a cross-section taken along lines 10—10 in FIG. 8, showing the contour of the surfaces in FIG. 8;

FIG. 11 is a top view of FIG. 7, the bottom view being a mirror image thereof; and,

FIG. 12 is a cross-section taken along the lines 12—12 in FIG. 8, showing the contour of the surfaces in FIG. 8.

The dashed lines and cross section lines in FIGS. 1—12 are to show the environment, and do not form a part of the claimed invention.
